UNITED STATES PATENT OFFICE.

ROBERT M. LOCKWOOD AND SAMUEL H. BARTLETT, OF NEW YORK, N. Y.,
ASSIGNORS OF ONE-HALF OF THEIR RIGHT TO CHARLES F. LIVERMORE,
OF SAME PLACE.

TRANSMITTER FOR TELEPHONES.

SPECIFICATION forming part of Letters Patent No. 228,826, dated June 15, 1880.

Application filed November 3, 1879.

To all whom it may concern:

Be it known that we, ROBERT M. LOCKWOOD and SAMUEL H. BARTLETT, both of the city, county, and State of New York, have invented certain Improvements in Transmitters for Telephones, of which the following is a specification.

This invention differs essentially from telephonic transmitters hitherto devised, for the reason that its effectiveness depends not upon the vibration or movement bodily of a diaphragm or equivalent to which the sound-waves of the air are directed, but upon a movement which may be termed "molecular," inasmuch as it is transmitted from molecule to molecule of a non-resonant transmitting material, which, as a body, remains stationary while serving as a conducting agent between the aerial sound-waves and the microphone which controls the volume, pitch, and variation of sound transmitted to and through the wires.

In the practice of the invention a microphone of any suitable character, and provided with suitable transmitting-wires, is supported and partially embedded in cork or light wood or other equivalent non-resonant material, so that when the sound-waves produced from the voice or other sound-producing agent are directed against the external surface of the non-resonant material a molecular disturbance in the structure of said material is set up, which, being communicated to the microphone, causes a similar disturbance therein, which, in its turn, modifies the conducting action of the voices in a proportionate degree, so that the original sound, modified as a manifestation of force in the course of its transmission, is reproduced at other portions of the circuit in a receiver of any appropriate kind.

Figures 1, 5, and 6 are sectional views representing a telephonic transmitter embracing our said invention. Figs. 2 and 3 show, in plan view, the parts included in Fig. 1; and Fig. 4 shows certain of the parts included in Fig. 6.

The microphone is composed of the two bars A A, the inner ends of which approach each other, but have a greater or less space between them. These bars are preferably of carbon,

of the kind well known to electricians, but may be of metal, which latter, however, so far as our experiments have extended, has been shown to be inferior to carbon. At or near the outer ends of these bars are attached suitable telephonic wires A' A'.

In the construction shown in Figs. 1, 2, and 5 the adjacent ends of the two bars are hollowed out so as to provide between them a circular opening, b. This opening receives the wooden stem c of a button, B, (said stem may be of any material not a conductor of electricity,) which should be of carbon or of other material suitable for the bars A A. The button B rests by gravity upon the upper surface of the inner ends of the bars A A.

The bars A A are embedded in or surrounded by a mass, C, of cork; or in lieu thereof, (but with inferior utility,) a mass of light wood or other non-resonant material possessing, so far as may be, the peculiar property of the cork, as hereinafter explained.

It is to be observed that the mass of non-resonant material C is chambered, as shown at B', said chamber receiving the inwardly-projecting inner ends of the bars, and also the button B, resting thereon.

In the operation of the apparatus the sound-waves produced in the air by the voice or other sound-producing agent strike the external surface of the cork, but from the inertness of the cork to vibratory action produce no vibration therein, but, on the contrary, transmit their force from molecule to molecule of the non-resonant mass, until the molecular motion reaches and is transmitted to the bars A A, and thence to the button B or its equivalent; but inasmuch as the degree of this molecular force varies with that of the impact on the external surface of the cork, it follows that the molecular action, in passing from the bars to the button, will be more or less modified, inasmuch as the surfaces of contact between the button, and the bars provide different conditions from those afforded in the homogeneous material of the bars themselves. This modification or disturbance in the relation of the button to the bars, although incapable of mechanical measurement, and itself consist-

ing rather in a changed condition of the points of contact of the touching-surface than in any change in their relative position, is responsive to every modification in the sound-waves brought to bear against the external surface of the cork, and the microphone, being thus responsive to every variation in the original sound, insures its transmission through the wires to any ordinary or appropriate receiver.

10 The office of the wooden pin in the button B is simply to retain the latter in position, the flat surface of the button resting upon the flat surfaces of the bars being found to give, upon the whole, better results than any other relation of the parts thus far devised.

15 The same results may be obtained by means of a cavity formed in and between the adjacent ends of the bars, to secure a simple ball or sphere of carbon or other suitable material, 20 as shown in Figs. 4 and 6; but the wedging of the ball in the socket is found, with this construction, to render its performance somewhat inferior to that of the button made as herein-before described.

25 When desired, the non-resonant material C may be confined between two metal plates or blocks, D D, as shown in Fig. 5.

We do not limit ourselves to the precise means herein described for carrying into ef-

fect our said invention, inasmuch as the same 30 may be widely varied by the exercise of the judgment of persons fairly skilled in the art to which our said invention relates, and inasmuch as we believe ourselves to be the first to devise a practical telephonic transmitter dependent for operation, not upon vibration or vibratory action, but upon the molecular transmission of force through a suitable non-resonant material.

35 We do not herein claim embedding the carbon plates or conductors wholly in a non-resonant substance, as that feature is made the subject of another application filed by us March 9, 1880; but

40 What we claim as our invention is—

Plates or bars of carbon or other conducting material arranged with their adjacent sides or ends out of contact, and having their opposite sides or ends firmly supported in a non-resonant material, in combination with the 45 interposed button, arranged and operating substantially as described.

R. M. LOCKWOOD.
